Frederick C. Gottschalk
Inventor
By his Attorney
Frank G. Kent

UNITED STATES PATENT OFFICE.

FREDERICK C. GOTTSCHALK, OF NEW YORK, N. Y.

DUPLICATING ROLL.

Application filed July 27, 1921. Serial No. 487,941.

To all whom it may concern:

Be it known that I, FREDERICK C. GOTTSCHALK, a citizen of the United States, residing at New York, in the county of New York and State of New York, have invented certain new and useful Improvements in Duplicating Rolls, of which the following is a specification.

This invention relates to duplicating rolls or sheets for duplicating machines, and has for its object to provide an improved form of roll or sheet which will be durable, from which the hektographic coating is not easily removed, which will not dry out and which is economical to manufacture and convenient to handle.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of invention:

Figure 1 is a plan view of a portion of a sheet embodying my invention, with successive component layers broken away; and

Figure 2 is a cross section.

Duplicating rolls or sheets have heretofore been manufactured in which the backing consisted of oiled paper, and sheets have also been made in which the backing consisted of oil cloth, or other fabric or relatively strong material, such as textiles. The use of oiled paper as a backing presents the advantage that the gelatinous duplicating composition does not dry out so readily, but there is the disadvantage that the paper tears rather easily. An oil cloth or fabric backing makes a more durable sheet, but when this is used the composition dries out more readily than where the oiled paper is used, probably by absorption of the glycerine component into the fabric. Accordingly, I propose to make a backing for the gelatinous duplicating composition which shall consist of a layer of oil cloth or textile fabric or similar relatively strong material, indi-

cated by the numeral 3, a layer of oiled or otherwise suitably treated paper 4, of a kind well known in this art as Kraft paper, treated with linseed oil to make it water and glycerine proof, united to the oil cloth layer by means of adhesive 5, which may be of any suitable composition, as for instance, glue-and-glycerine, the gelatinous duplicating composition, which is indicated by the numeral 6, being supplied and adhering to the outer surface of the paper layer 4. Preferably the rough surface of the oil cloth (assuming that oil cloth is used having only one smooth face) is inward, so that the adhesive unites readily and firmly therewith, and so that when the sheet is rolled up the smooth face of the oil cloth comes in contact with the gelatin surface and adhesion between the two is minimized.

A sheet or roll made up as set forth is durable and not easily torn, because of the nature of main backing 3; the duplicating composition will retain its glycerine, because the linseed-oil-treated paper is comparatively impervious to glycerine, and further, possibly, because the underlying adhesive 5 contains glycerine; and where an oil cloth is used as the backing 3, with a finished face outwardly, adhesion between it and the hektographic layer 6 when the sheet is rolled up, is minimized.

Inasmuch as many changes could be made in the above construction, and many apparently widely different embodiments of my invention could be made without departing from the scope thereof, it is intended that all matter contained in the above description, or shown in the accompanying drawings, shall be interpreted as illustrative and not in a limiting sense.

It is also to be understood that the language used in the following claims is intended to cover all the generic and specific features of the invention herein described and all statements of the invention which, as a matter of language, might be said to fall therebetween.

I claim:

1. A duplicating roll comprising a backing of relatively strong fabric, a paper layer adhesively united thereto and a layer of duplicating composition on the paper layer.
2. A duplicating roll comprising a backing of relatively strong fabric, an oil-treat-

ed paper layer adhesively united thereto, and a layer of duplicating composition on the paper layer.

3. A duplicating roll comprising a backing of relatively strong fabric, a glycerine-proof paper layer adhesively united thereto, and a layer of duplicating composition on the paper layer.

4. A duplicating roll comprising a backing of oil-cloth, having a rough face and a finished face, a glycerine-proof paper adhe-

sively united to the rough face thereof, and a layer of duplicating composition on the paper layer.

5. In a duplicating roll, a reinforcing 15 backing of relatively strong fabric, a layer of suitably treated paper to render the same water and glycerine proof affixed thereto and a layer of duplicating composition on the paper.

In testimony whereof I affix my signature.

FREDERICK C. GOTTSCHALK.
